JOHN P. COLEMAN, OF EDGEWOOD BOROUGH, PENNSYLVANIA, ASSIGNOR TO THE UNION SWITCH AND SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 24, 1925. Serial No. 58,323.

My invention relates to railway traffic controlling apparatus, and particularly to apparatus of the type comprising a traffic controlling device controlled by a manually operable lever through the medium of a valve and a fluid pressure motor.

One object of my invention is the provision, in apparatus of the type described, of means for limiting the movement of the lever unless both the valve and the traffic controlling device are in predetermined relative positions.

I will describe one form of railway traffic controlling apparatus embodying my invention, and will then point out the novel features thereof in claims.

In the accompanying drawings, Fig. 1 is a view, partly diagrammatic, illustrating one form of railway traffic controlling apparatus embodying my invention. Fig. 2 is a fragmental view showing a part of the switch valve C illustrated in Fig. 1. Fig. 3 is a sectional view along line III-III of Fig. 2.

Similar reference characters refer to similar parts in each of the three views.

Referring first to Fig. 1, the reference characters 1 and 1^a designate the rails of a stretch of railway track which is provided with a traffic controlling device, here illustrated as a switch 2 of the usual and well known form. This switch is operated by a fluid pressure motor A comprising a cylinder 3 containing a reciprocable piston 4. Attached to the piston 4 is a plunger 5 which is operatively connected with the movable points of the switch 2 through suitable mechanism which is indicated by the dotted line 5^a.

The motor A is controlled by a switch valve C comprising a slide valve 7 operating in a valve chamber 6. The chamber 6 is constantly supplied with fluid pressure, from a source not shown in the drawing, through pipe 11. When the slide valve is in its normal position, fluid pressure is supplied from chamber 6, through pipe 10 to the lower end of cylinder 3 of motor A and the upper end of this cylinder is connected with atmosphere through pipe 8 and port 9. With the valve in this position therefore the piston 4 is moved upwardly and the switch then occupies what I shall herein-after term its "normal" position. When the

slide valve 7 occupies its reverse position, 55 pipe 8 is connected with chamber 6, and pipe 10 is connected through port 9 to atmosphere. The piston 4 is then driven downwardly and the switch 2 is moved to its reverse position. 60

The valve 7 is provided with two spaced notches 15 and 16 arranged to receive a locking rod 17 when the valve is in the reverse or normal position, respectively. The rod 17 carries an armature 18 associated with a winding 19, and is constantly urged toward the slide valve 7 by a spring 20. When winding 19 is energized, however, armature 18 is moved outwardly thereby disengaging the rod 17 from the notches in the 70 slide valve and permitting the valve to be shifted by means which I will describe hereinafter. It will be plain, however, that the valve can be shifted only when winding 19 is energized to lift the rod 17 clear of the 75 valve.

The switch valve C also comprises two oppositely disposed axially aligned cylinders 12 and 12^a. The cylinder 12 contains a piston 13 carrying a stem 14 which engages one 80 end of the slide valve 7, and the cylinder 12^a contains a piston 13^a carrying a stem 14^a which engages the other end of the slide valve 7. Cylinder 12 is at times supplied with fluid pressure by a valve 21 comprising 85 a valve stem 23 provided with a winding 25 and an armature 24 associated therewith. When winding 25 is de-energized the valve stem 23 occupies its left-hand position and cylinder 12 is connected with atmosphere. 90 When winding 25 of valve 21 is energized, however, the valve stem 23 is moved to the right and cylinder 12 is then disconnected from atmosphere and is connected with a source of fluid pressure. In similar manner 95 a valve 22 controls the supply of fluid pressure to cylinder 12^a so that when winding 25^a of valve 22 is de-energized, cylinder 12^a is connected with atmosphere but that when this winding is energized cylinder 12^a is supplied with fluid pressure. It will be plain 100 from the drawing that when cylinder 12^a is supplied with fluid pressure, piston 13^a is moved upwardly to drive the valve 7 to its normal position. When cylinder 12 is supplied with fluid pressure, however, piston 13 moves downwardly and drives the valve 7 to its reverse position. In either case, of 105

course, movement of valve 7 is possible only if the locking rod 17 is withdrawn from the notches 15 and 16.

The windings 25 and 25^a of valves 21 and 22 and winding 19 are controlled by a manually operable lever designated in general by the reference character L. This lever comprises a handle 33 and a plurality of contacts arranged to be open or closed in accordance with the position occupied by this handle. The diagram appearing immediately below the handle 33 in Fig. 1 of the drawings illustrates the principal positions which may be occupied by the lever. It will be seen from the drawing that the lever may occupy its full "normal" or left-hand position N, its full "reverse" or right-hand position R, or either of two intermediate positions customarily designated as the "reverse indicating" position D, and the "normal indicating" position B. The various contacts are designated by reference characters which correspond to this diagram and which indicate the positions between which the associated contacts is closed. For example, the lowest contact on the lever L is designated by the reference character NB which means that this contact is closed when the lever L is in the normal position, the B position, or any position between these two.

The circuit for winding 19 may be traced from a suitable source of energy, such as a battery P, through line wire 37, wire 66, contact BD of lever L, wire 67, winding 19 and wires 68 and 69 and line wire 38 back to battery P, the circuit for winding 25 of valve 21 passes from line wire 37, through wires 66 and 70, contact DR of lever L, wire 71, winding 25 of valve 21, and wire 69 back to line wire 38. When contact NB of lever L is closed, current flows from line wire 37, through wires 66 and 72, contact NB of lever L, wire 73, winding 25^a of valve 22, and wires 74 and 69 back to line wire 38.

Associated with lever L are a normal indication lock K and a reverse indication lock J. Each of these indication locks comprises a segment 36 operatively connected with the lever L and a magnet 34 having a locking dog 35 controlled thereby. Segment 36 of lock K is provided with a projection 36^a so arranged that when the lever is moved from the reverse position toward the normal position the dog 35 engages the projection 36^a and prevents movement of the lever past the normal indicating position B unless magnet 34 is energized. In similar manner segment 36 of lock J is provided with a projection 36^b which is arranged to be engaged by the dog 35 at the D position when the lever is moved from the normal position toward the reverse position unless the magnet 34 is energized. The magnets 34 of the indication locks K and J are controlled by a

polarized indication relay E and by the usual quick acting contacts of the lever L. The circuit for the magnet of lock K passes from line wire 37, through wire 55, front contact 56 of relay E, wire 57, normal contact 58 of relay E, wire 59, contact RB of lever L, wire 60, magnet 34 of lock K and wire 62 back to line wire 38. The reverse locking circuit passes from line wire 37, through wire 55, front contact 56 of relay E, wire 57, reverse contact 63 of relay E, wire 64, contact ND of lever L, wire 65, magnet 34 of lock J and wires 61 and 62 back to line wire 38.

The relay E is controlled by two circuit controllers G and H. Circuit controller H comprises a movable contact member 29 operatively connected with the movable points of the switch 2. When the switch 2 is in the normal position, in which it is illustrated in the drawing, member 29 occupies its normal position in which it engages with two fixed contact fingers 30 and 30^a. When the switch is in its reverse position, member 29 occupies its reverse position in which it engages a second pair of contact fingers 32 and 32^a. When the switch occupies any intermediate position the member 29 occupies a corresponding intermediate position and engages a third pair of contact fingers 31 and 31^a.

The circuit controller G comprises a movable contact member 26 which is operatively connected with the slide valve 7 so that the position of the member 26 is determined by the actual position of the slide valve. When the slide valve is in its normal position member 26 engages fingers 27 and 27^a, but when the slide valve occupies its reverse position, member 26 engages fingers 28 and 28^a. When the slide valve is in its normal position and the switch 2 is also in its normal position, current flows from line wire 37, through wires 39 and 40, contact 30-29-30^a of circuit controller H, wires 41 and 42, winding of relay E, wires 43, 44 and 45, contact 27-26-27^a of circuit controller G and wires 46 and 47 back to line wire 38. When this circuit is closed relay E is supplied with current of such polarity that the relay is energized in the normal direction and contact 58 is closed. When switch 2 is in its reverse position and the slide valve 7 is also in its reverse position current flows from line wire 37, through wires 39 and 48, contact 28^a-26-28 of circuit controller G, wires 49, 44 and 43, winding of relay E, wires 42, 50 and 51, contact 32^a-29-32 of circuit controller H, and wires 52 and 47 back to line wire 38. When this circuit is closed the current supplied to relay E is of such polarity that the relay is energized in the reverse direction and contact 63 is closed. It should be pointed out that should the position of the slide valve not correspond

130

to the position of switch 2, that is, should the slide valve be in the normal position when the switch is in the reverse position, or vice-versa, relay E will be de-energized and 5 front contact 56 of the relay will be open. It should also be pointed out that during transit of the switch or at any time when the switch is not in the full normal or full reverse position the closing of contact 10 31-29-31^a of circuit controller H short circuits relay E and causes the front contact 56 of this relay to open.

As shown in the drawing the lever L occupies the normal position so that winding 15 25^a of valve 22 is energized. Cylinder 12^a is therefore supplied with fluid pressure and valve 7 occupies its normal position. Contact BD of lever L is open so that winding 20 19 is de-energized and rod 17 enters groove 16 to lock the slide valve in position. Contact DR of lever L is also open so that winding 25 of valve 21 is de-energized. Since 25 valve 7 is in its normal position fluid pressure is supplied to the lower end of cylinder 3 of motor A and switch 2 occupies its normal position. Since the slide valve 7 and the switch 2 both occupy their normal positions, relay E is energized in the normal direction. The circuit for magnet 34 of lock 30 K is open at contact RB of lever L and the circuit for magnet 34 of lock J is open at reverse contact 63 of relay E.

In explaining the operation of the apparatus I will first assume that the operator 35 in charge of lever L wishes to reverse switch 2. Lever L is first moved toward the reverse position. Magnet 34 of the reverse indication lock J is de-energized, however, so that the movement of the lever is arrested 40 at the D position. The movement of the lever from the N to the D position de-energizes winding 25^a of valve 22 and energizes winding 25 of valve 21. Cylinder 12 is therefore supplied with fluid pressure and cylinder 12^a is connected with atmosphere. The closing of contact BD of lever L also 45 completes the circuit for winding 19 so that the rod 17 is lifted out of engagement with the slide valve 7, and the valve is therefore moved to its reverse position by piston 13. The reversal of slide valve 7 connects the lower end of cylinder 3 with atmosphere and supplies fluid pressure to the upper end of this cylinder. The switch 2 is therefore 50 moved to its reverse position. When the switch has attained its full reverse position the closing of contact 32-29-32^a of circuit controller H completes a circuit for relay E whereby this relay becomes energized in the 55 reverse direction. It should be particularly pointed out that this circuit is closed only if the slide valve also occupies its reverse position. The closing of reverse contact 63 of relay E completes the circuit for magnet 34 of lock J. Dog 35 of this lock is there-

fore lifted to permit the movement of lever L to be completed to its full reverse position R. As a result of this movement of lever L, contacts ND and BD become opened; the opening of contact ND de-energizes 70 the magnet 34 of lock J, and the opening of contact BD de-energizes winding 19 so that rod 17 enters groove 15 to lock the slide valve in its reverse position. Winding 25 of valve 21 remains in its energized 75 condition, however, contact DR remaining closed. If the operator wishes to restore the switch to its normal position he first moves the lever L from the reverse position to the normal indicating position, B, where the 80 lever is locked against further movement by engagement of dog 35 of lock J with projection 36^a of segment 36. With the lever L in the B position winding 19 is energized so that the rod 17 is withdrawn from engagement with the valve 7, winding 25 of valve 21 is de-energized, and winding 25^a of valve 22 is energized. The slide valve 7 is therefore restored to its normal position. As a result of this motion of valve 7 the 85 piston 4 of motor A moves to its normal position, thereby driving the switch 2 to its normal position. With the slide valve 7 and the switch 2 both occupying their normal positions a circuit is closed for relay E by 90 virtue of which contact 56 of this relay is closed. Contact RB of lever L is already closed so that current is now supplied to magnet 34 of lock K. Dog 35 of this lock is therefore lifted out of engagement with 95 the projection 36^a of segment 36 and the operator can complete the movement of the lever L to the full normal position. The consequent opening of contact BD de-energizes winding 19 and allows rod 17 to enter 100 groove 16 in the slide valve 7 to lock the valve in its normal position.

One form of switch valve C suitable for operation as hereinbefore described is illustrated in Letters Patent of the United States 110 No. 1,233,729, granted on the 17th day of July, 1917, to P. Utne, for railway traffic controlling apparatus.

Referring now to Figs. 2 and 3 I have illustrated one arrangement of apparatus for 115 controlling the movable member 26 of the circuit controller G in response to the position occupied by the slide valve 7 in a switch valve such as illustrated in the patent referred to in the preceding paragraph. In 120 this apparatus the reference character 75 designates the valve body containing the valve chamber 6 and the slide valve 7. This valve body supports the cylinders 12 and 12^a containing the pistons 13 and 13^a respectively. 125

As best shown in Fig. 3 I prefer to mount on the valve body 75, two spaced base plates 81 and 85 extending parallel to the direction of motion of the slide valve 7. Mounted upon the base plate 81 is a spacing member 83 130

and a supporting member 82, and a similar spacing member 87 and supporting member 86 are mounted upon the base plate 85. The parts are so constructed that a channel 84 is formed between the supporting member 82 and the base plate 81, and a similar oppositely disposed channel 88 is formed between the supporting member 86 and base plate 85. A driving plate 78 of inverted U-shape is mounted to reciprocate in the channels 84 and 88 and carries the movable contact member 26. The downwardly turned ends 78^a of the driving plate 78 enter recesses 89 milled in the top of the valve body 75. This valve body is drilled at 76 to receive a plunger 77 one end of which engages the left-hand face of piston 13. The valve body is also drilled at 76^a to receive a plunger 77^a which engages the right-hand face of piston 13^a. The parts are so proportioned that the inner opposing faces of the plungers 77 and 77^a abut against the downwardly turned ends 78^a of the driving plate 78. The plate 78 carries an insulating member 79 to which is attached the movable contact member 26. It will be plain from the drawing, and from the description of the operation hereinbefore set forth, that when pistons 13 and 13^a occupy their right-hand positions (as seen in Fig. 2) corresponding to the normal position of the slide valve, the driving plate 78 and the movable contact member 26 carried thereby are moved to the right, and when the pistons 13 and 13^a occupy their left-hand positions (as seen in Fig. 2) corresponding to the reverse position of slide valve 7, the driving plate 78 and the movable contact member 26 are moved to their left-hand positions. The supporting members 82 and 86 may be utilized to support fixed contacts 27-27^a, 28-28^a (Fig. 1) in such manner that the operation of the circuit controller will conform with the description hereinbefore contained. These fixed contacts are omitted from Figs. 2 and 3 in order to simplify the drawings.

For purposes of clearness I have described one arrangement of apparatus for controlling the circuit controller G in accordance with the actual position of the slide valve 7 but I do not wish to limit myself to the particular arrangement of apparatus which I have shown.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a switch operating cylinder,

means including a slide valve for admitting fluid pressure to one end of said cylinder or the other according as said valve occupies a normal or a reverse position, means including a manually operable lever for shifting said valve, and a circuit controller operatively connected with said valve for governing movements of said lever.

2. Railway traffic controlling apparatus comprising a switch operating cylinder, means including a slide valve for admitting fluid pressure to one end of said cylinder or the other according as said valve occupies a normal or a reverse position, two fluid pressure motors for moving said slide valve to its normal and reverse positions respectively, means including a manually operable lever for supplying fluid pressure to one or the other of said motor, and a circuit controller operatively connected with said slide valve for governing movements of said lever.

3. Railway traffic controlling apparatus comprising a switch operating cylinder, means including a slide valve for admitting fluid pressure to one end of said cylinder or the other according as said valve occupies a normal or a reverse position, two fluid pressure motors for moving said slide valve to its normal and reverse positions respectively, two magnets for controlling the supply of fluid pressure to said two motors respectively, means including a manually operable lever for energizing one or the other of said magnets, and a circuit controller operatively connected with said slide valve for governing movements of said lever.

4. Railway traffic controlling apparatus comprising a switch operating cylinder, means including a slide valve for admitting fluid pressure to one end of said cylinder or the other according as said valve occupies a normal or a reverse position, two fluid pressure motors for moving said slide valve to its normal and reverse positions respectively, two auxiliary valves for admitting fluid pressure to one or the other of said motors, two magnets for controlling said two auxiliary valves respectively, means including a manually operable lever for controlling the supply of current to said magnets, and a circuit controller operatively connected with said slide valve for governing movements of said lever.

5. Railway traffic controlling apparatus comprising a cylinder, a piston operating therein, a railway switch actuated by said piston, means including a slide valve for admitting fluid pressure to one end of said cylinder or the other according as the valve occupies a normal or a reverse position, means including a manually operable lever for shifting said slide valve, and means for controlling said lever jointly by the position of said slide valve and the position of said switch.

6. Railway traffic controlling apparatus comprising a cylinder, a piston operating therein, a railway switch actuated by said piston, means including a slide valve for admitting fluid pressure to one end of said cylinder or the other according as said valve occupies a normal or a reverse position, means including a manually operable lever for shifting 70 said valve, a circuit controller operatively connected with said valve and including a normal and a reverse contact which contacts are closed when the valve is in the normal and reverse positions respectively, and 75 means controlled by said contacts for governing movements of said lever.
- 10 7. Railway traffic controlling apparatus comprising a cylinder, a piston operating therein, a railway switch actuated by said piston and having a normal and a reverse position, a slide valve for admitting fluid pressure to one end or the other of said cylinder to move said switch to its normal or its reverse position according as the valve is in a normal or a reverse position, a manually operable lever having normal and reverse positions, means responsive to movement of said lever towards its reverse position for moving said slide valve to its reverse position, means responsive to movement of said lever towards its normal position for moving said slide valve to its normal position, and means for preventing movement of said lever to its full reverse or its full normal position unless both said slide valve and said switch are in reverse or normal positions.
- 15 8. Railway traffic controlling apparatus comprising a cylinder, a piston operating therein, a railway switch actuated by said piston and having a normal and a reverse position, a slide valve for admitting fluid pressure to one end or the other of said cylinder to move said switch to its normal or its reverse position according as the valve is in a normal or a reverse position, a manually operable lever having normal and reverse positions, means responsive to movement of said lever towards its reverse position for moving said slide valve to its reverse position, means responsive to movement of said lever towards its normal position for moving said slide valve to its normal position, a circuit controller operated by said slide valve and including a normal and a reverse contact closed when the valve occupies its normal and reverse positions respectively, a circuit controller operated by said switch and including a normal and a reverse contact closed when the switch occupies its normal and reverse positions respectively, and means for preventing movement of said lever to its full reverse or its full normal position unless both said reverse contacts or both said normal contacts are closed.
- 20 9. Railway traffic controlling apparatus comprising a switch operating cylinder,
- 25 means including a slide valve for admitting fluid pressure to one end of said cylinder or the other according as said valve occupies a normal or a reverse position, means including a manually operable lever for shifting 70 said valve, a circuit controller operatively connected with said valve and including a normal and a reverse contact which contacts are closed when the valve is in the normal and reverse positions respectively, and 75 means controlled by said contacts for governing movements of said lever.
- 30 10. Railway traffic controlling apparatus comprising a manually operable lever having a normal and a reverse position, a valve 80 having a normal and a reverse position, means effective when said lever is moved toward its reverse position for moving said valve to its reverse position, a traffic controlling device having a normal and a reverse position, means for moving said device to its reverse position when said valve is moved to its reverse position, and means for preventing movement of said lever to its full reverse position unless said valve is in 85 its reverse position.
- 35 11. Railway traffic controlling apparatus comprising a manually operable lever having a normal and a reverse position, a valve having a normal and a reverse position, 90 means effective when said lever is moved toward its reverse position for moving said valve to its reverse position, a traffic controlling device having a normal and a reverse position, means for moving said device to its 100 reverse position when said valve is moved to its reverse position, and means for preventing movement of said lever to its full reverse position unless said valve and said device are both in their reverse positions. 105
- 40 12. In combination, a switch valve comprising a slide valve, pistons for operating said slide valve, a manually operable lever, means controlled by said lever for positioning said pistons, a contact member operatively connected with said pistons, and means responsive to the position of said contact member for at times limiting the movement of said lever.
- 45 13. The combination with a switch valve 115 comprising a slide valve and a piston for operating said slide valve, of a circuit controller comprising a movable contact member operatively connected with said piston.
- 50 14. The combination with a switch valve 120 comprising a valve body containing a slide valve and a piston for operating said slide valve, of a plunger passing through said body and engaging said piston, and a circuit controller comprising a contact member controlled by said plunger.
- 55 15. The combination with a switch valve 125 comprising a valve body containing a slide valve, and a pair of aligned cylinders provided with two pistons one in each cylinder 130

for operating said slide valve, of two aligned plungers passing through said valve body and engaging said two pistons respectively, a movable plate interposed between said 5 plungers outside said valve body, and a circuit controller comprising a contact member operatively connected with said plate.

16. The combination with a switch valve

comprising a slide valve and fluid pressure motor device for operating said slide valve, 10 of a circuit controller comprising a movable contact member operatively connected with said slide valve.

In testimony whereof I affix my signature.

JOHN P. COLEMAN.
